UNITED STATES PATENT OFFICE.

DELPLAIN B. MONROE, OF ENDICOTT, NEW YORK.

CRUTCH.

1,107,981.

Specification of Letters Patent.

Patented Aug. 18, 1914.

Application filed February 27, 1914. Serial No. 821,474.

To all whom it may concern:

Be it known that I, DELPLAIN B. MONROE, a citizen of the United States, residing at Endicott, in the county of Broome and State 5 of New York, have invented certain new and useful Improvements in Crutches; and I do hereby declare the following to be a full, clear, and exact description of the invention, such as will enable others skilled 10 in the art to which it appertains to make and use the same.

This invention relates to crutches such as are employed by injured or crippled persons for aiding them in walking about, and the 15 primary object of the same is the provision of a crutch having a cushioned or resiliently supported arm rest for absorbing the shock occasioned by compact of the crutch leg with the ground or pavement during the walking.

With the foregoing and other objects in view this invention consists in such novel features of construction, combination and arrangement of parts as will be hereinafter 20 more fully described, illustrated in the accompanying drawings and claimed.

In describing the invention in detail reference will be had to the accompanying drawings wherein like characters of reference designate like and corresponding parts 25 throughout the several views, and in which:—

Figure 1 is a view of the improved crutch in elevation. Fig. 2 is an enlarged detailed sectional view of the upper end of the crutch 30 showing the resilient supporting of the arm rest. Fig. 3 is a cross sectional view on the line 3—3 of Fig. 2. Fig. 4 is a detail view in elevation of the arm rest. Fig. 5 is a detail perspective view of a sleeve employed 35 in the resilient supporting of the arm rest. Fig. 6 is a detail perspective view of a part of the arm rest structure, and Fig. 7 is a detail plan view of a fragment of the arm rest.

Referring to the drawings by numeral, 1 40 designates the crutch as an entirety, which is of the usual construction of split crutch, having the leg thereof constructed of a single piece of toughened wood, which is split at 2, to provide the arms 3 and 4. The foot 45 of the leg of the crutch 1 has a rubber cushion 5 mounted thereon so as to prevent the crutch from slipping and to provide a firm contact with the ground or pavement during the walking with the crutch.

The two arms 3 and 4 of the crutch leg are held apart and braced by a handle 6, which

handle extends laterally from one arm to the other, at a convenient distance from the upper end of the crutch to be gripped by the hand of the person using the same. The 60 crutch arms 3 and 4 are braced and strengthened by the plates 7, which are secured thereto adjacent the portion of the crutch arms to which the handle 6 is attached, by any suitable means such as rivets or screws 65 8. The upper ends 9 of the crutch arms are braced and properly held in position by substantially U-shaped brackets 10, one of which is connected to each of the arms and extend inwardly toward each other, having 70 their vertices secured to each other and the terminal ends of their legs secured to the crutch arms as is obvious by reference to Fig. 1 of the drawings. The upper terminal ends of the arms 3 and 4 of the crutch 1 are 75 reduced in diameter and have the enlarged ends 11 of sleeves 12 mounted thereupon which sleeves are held from rotation by pins 13.

Pins 14 are centrally mounted in the upper ends of the arms 3 and 4 and project upwardly therefrom, having coil springs 15 loosely mounted thereabout. The springs 15 are seated within the sleeves 12 and have their lower ends abutting the upper terminal ends of the arms 3 and 4, while the upper ends of the springs engage the lower ends of filling material 16 which is disposed within the sleeves 17.

The sleeves 17 are slidably mounted upon 90 the reduced ends of the sleeves 11, and are securely attached to a U-shaped supporting frame 18. The sleeves 17 have lugs 19 formed upon their upper ends, which lugs are inserted through openings 20 formed in 95 the U-shaped support 18, and upset to securely rivet or attach the sleeves to the supporting member.

The pins 14 are provided with longitudinally extending slots 22 formed in their upper ends, in which slots are slidably seated bolts 23. The bolts 23 pass through the sleeves 17 and the filling washers 16 and prevent the rotation or rotary movement of the sleeves 17 upon the reduced portion of 105 the sleeves 11, also forming guides for the vertical movement of the sleeves and the substantially U-shaped support 18.

The legs 23 and 24 of the substantially U-shaped support 18, which extend upwardly 110 in alignment with the vertical longitudinal lines of the arms 3 and 4 on the crutch have

horizontally extending pins 25 secured there-
to near their upper ends. The pins 25 have
reduced shanks 26, which are provided with
external screw threads. The reduced shanks
5 26 of the pins 25 are inserted through open-
ings in the legs 23 and 24 and the pins are
securely attached to the legs by means of the
shanks and nuts 27 which are mounted upon
the terminal ends of the shanks 26 and hold
10 the shoulders 28 of the pins 25 in binding
engagement with the inner surface of the
legs 23 and 24. The pins 26 have openings
29 extending therethrough, in which open-
ings are seated the terminal ends of a coil
15 spring 30. The coil spring 30 extends lat-
erally between the legs 23 and 24 of the sup-
port 18 and is covered with a double coating
of leather or other similar cushioning mate-
rial to prevent the coils of the wire from
20 mutilating the clothes of the person who is
using the crutch, as well as to prevent the
coils from pinching the flesh during the
downward movement of the spring owing to
the pressure or weight applied thereon.

25 The outer coating 33 of leather is provided
with ears 34 formed upon its ends, which
ears extend about the portions of the legs 23
and 24 adjacent the nuts 27 and have their
30 terminal ends secured to the end of the cov-
ering 33 by stitching or other suitable secur-
ing means.

35 The coil spring 30 forms a rest for the arm
of the person using the crutch, and is placed
in the pit of the arm, or the under portion of
the connection between the arm and the
shoulder, as is obvious in the use of a crutch
40 of this nature and being constructed of a coil
spring, it will provide a resilient arm rest,
which will give and yield under the move-
ment of the arm and shoulder, thereby pro-
viding a non-irritating and comfortable rest
45 for the arm.

By the provision of the coil springs 15,
which are mounted in the sleeves 11 and 17,
45 further resiliency is added to the upper end

of the arm resting portion of the crutch, so
that the shocks occasioned by the compact of
the foot of the crutch 1 with pavement or
ground, during the using of the crutch will
be absorbed and not imparted to the shoul- 50
der of the user.

What is claimed is:—

1. In a crutch, a crutch leg having a sub-
stantially U-shaped support mounted upon
its upper end, and a coil spring suspended 55
between the legs of said U-shaped support
and forming an arm rest for yieldable con-
formity to the movement of the arm of a
person.

2. In a crutch, a crutch leg being split to 60
form arms, sleeves mounted upon the upper
terminal ends of said arms, a substantially
U-shaped support, sleeves depending from
the vertex of said U-shaped member and
slidably mounted upon said first named 65
sleeves, coil springs mounted within said
sleeves for resiliently supporting said U-
shaped support, and a yieldable arm rest
suspended between the legs of said U-shaped
support for yieldable conformity to the 70
movement of the arm of a person.

3. In a crutch, a crutch leg being split to
form arms, sleeves mounted upon the upper
terminal ends of said arms, a substantially
U-shaped support, sleeves depending from 75
the head of said U-shaped support and slid-
ably mounted upon said first named sleeves,
coil springs disposed within said sleeves for
resiliently supporting said U-shaped sup-
port, a coil spring suspended between the 80
legs of said U-shaped support and forming
a yieldable arm rest for conformity to the
movement of the arm of a person, and a
cover about said coil spring.

In testimony whereof I affix my signature 85
in presence of two witnesses.

DELPLAIN B. MONROE.
